UNITED STATES PATENT OFFICE.

VITALIS HIMMER, OF MOUNTAIN LAKES, NEW JERSEY.

LOUD SPEAKER.

Application filed March 23, 1925. Serial No. 17,507.

This invention relates to improvements in acoustical devices, and has particular reference to an instrument capable of reproducing and amplifying sound vibrations transmitted by a record or equivalent element, or by electrical carrier waves.

It has heretofore been proposed to make diaphragms for sound reproducers of light vibratile material, such as paper, and to form 10 a portion of the diaphragm into cone shape with the periphery thereof rigidly secured between clamping rings and the diaphragm itself freely exposed to unconfined air. It has been claimed for such construction that 15 vibrations impressed upon the apex of the cone will be transmitted to the conical portion of the diaphragm so that said portion will be bodily moved with no wave motions set up therein.

According to the present invention it is proposed to provide a conical diaphragm responsive to vibrations of a wide range of frequency, the periphery of said diaphragm being freely supported so that the vibrations 20 imparted to the diaphragm will bodily move the same throughout its entire area. A diaphragm constructed in this manner will reproduce vibrations accurately and with satisfactory tone quality. However, it 25 has been found that, by making the diaphragm of conical formation throughout its entire area and providing the same with a support which permits of a free movement of the periphery thereof and which combines with said diaphragm to form a partially exposed resonance chamber so that 30 the diaphragm will not vibrate entirely in free air, the resultant tones have a distinctive, highly pleasing and resonant quality. 35 which is lacking when the surfaces of the diaphragm are entirely exposed to an unconfined air space.

Furthermore, it has been discovered that a reproducer constructed as above set forth 40 will more accurately register sound vibrations of all audible frequencies when the periphery of the diaphragm, which is secured to its support by an adhesive, is also fastened thereto with a binding element of 45 flexible material. During the drying process following the application of the adhesive to the diaphragm and its support and the binding thereof with said element, there 50 will be an uneven shrinking of the periphery of the diaphragm which will result in more

or less strain being applied to different portions of said periphery by said binding element. Therefore, when the diaphragm is vibrated the portions under greater strain will accurately produce vibrations of a 60 higher frequency, while those under a lesser strain will faithfully register vibrations of a lower frequency.

It is further proposed to reinforce the diaphragm about its apex so as to impart 65 a graduated rigidity to the diaphragm for a considerable area about its apex, which rigidity will be decreased as the periphery of the diaphragm is approached.

The inventive idea involved is capable of 70 receiving a variety of mechanical expressions some of which, for the purpose of illustration, are shown in the accompanying drawings; but it is to be expressly understood that said drawings are used merely 75 for the purpose of illustrating the invention as a whole and not to define the limits thereof, reference being had to the appended claims for this purpose.

In the drawings—

Figure 1 is a side elevation, partly broken away and shown in section, of an acoustical device constructed in accordance with the invention;

Figure 2 is a rear elevation thereof, partly 85 broken away;

Figure 3 is an enlarged fragmentary sectional view showing the construction of the apex of the diaphragm;

Figure 4 is a similar view showing the 90 construction at the periphery of the diaphragm;

Figure 5 is an end elevation of a slightly 95 different form of the invention;

Figures 6 and 7 are views similar to Figure 4, also showing slightly different forms of the invention;

Figure 8 is a side elevation illustrating 100 the application and use of the invention in connection with a phonograph record having a groove of the vertically undulating type; and

Figure 9 is a similar view showing the 105 application of the invention to a phonograph record having a groove of the laterally undulating type.

The device of the present invention is primarily designed as a so-called loud speaker for radio receiving apparatus, but its construction also permits of the same be- 110

ing employed as a sound reproducer for talking machines. In either instance the essential characteristics of the device are the same.

Referring more particularly to Figures 1 to 4, the device is shown as comprising a ring member 10 made of any suitable material, such as wood, and forming a rigid support for the various elements constituting the device, said ring being capable of being attached thereto in any desired manner a standard 10' utilized to support the device in a vertical position when employed as a loud speaker. The inner face of the ring 10 is preferably beveled, as indicated at 11, and the beveled portion is adapted to have secured thereto, by a suitable adhesive, the inner rim of a flexible frusto-conical support 12 which carries the conical diaphragm 13. Both the support 12 and the diaphragm 13 are made of a light vibratile material, preferably paper of suitable thickness, and the same are formed by cutting a segment from a circular sheet and then contracting the sheet and binding the free edges by a suitable adhesive. Preferably the side of the diaphragm 13 is arranged at a greater inclination than that of the support 12, but it is to be understood that the relative inclination of said sides may be varied at will without departing from the spirit or scope of the invention. The support 12 and diaphragm 13 combine to form a resonance chamber, the depth of which is controlled by the relative inclination of said support and diaphragm. It will be apparent that by the formation of this resonance chamber the outer surface of the diaphragm 13 will be entirely exposed to unconfined air, while the inner surface thereof will be partially exposed due to the openings in the support and rigid supporting ring which openings are of less diameter than the width of the support from its periphery to the edge of the opening therein.

The diameter of the support 12 is such that when the same is placed in juxtaposition to the diaphragm 13 the outer periphery of the support will engage the inner surface of the diaphragm at a distance from the periphery of the latter, as clearly shown in Figure 4. In other words, when the support and the diaphragm are assembled an annular portion of the diaphragm at its periphery will extend outwardly beyond the periphery of the support. This is done to provide an adequate surface to which an adhesive, indicated by the numeral 14, may be applied for it will be obvious that if the peripheries of the elements 12 and 13 were brought together and secured by an adhesive applied to the contacting edges thereof there would be insufficient contacting surface to adequately maintain the connection between said elements. By joining the sup-

port and diaphragm in the manner illustrated the area of the surface to which the adhesive 14 may be applied will be greatly increased and by reason of this fact the connection between said elements will be strengthened. It has been found in practice that after the application of the adhesive 14 a certain amount of uneven shrinkage thereof occurs which has a tendency to slightly distort the diaphragm 13 adjacent its periphery. Discovery has been made that if the diaphragm is held by an additional binding element when this slight distortion takes place more or less strain will be applied to different portions of the diaphragm with the result that when the diaphragm is vibrated the portions under greatest strain will accurately reproduce vibrations of a higher frequency, while those portions under a lesser strain will aid in clearly reproducing vibrations of a lower frequency. To the end that these results may be accomplished the invention includes a binding element 15 of any flexible material which is extended about the periphery of and secured to the diaphragm 13 and overlapped with the periphery of the support 12. This binding element 15 also provides an additional reinforcement for the peripheries of the support and diaphragm which will greatly minimize the possibility of said peripheries becoming separated when undue shocks are imparted to the structure.

In Figures 6 and 7 different forms of attaching the support to the diaphragm are illustrated. The elements in this instance may be made of the same diameter and their peripheries flattened so as to provide more or less contacting surface therebetween. As shown in Figure 6 these contacting surfaces may be secured together by an adhesive and are of sufficient width to permit of a further securing thereof by a double row of stitching 16. In Figure 7 the contacting surfaces are relatively narrow and simply secured by a single row of stitching 17. The apex of the diaphragm 13 is provided with a small opening 18 and said apex is reinforced around the opening by a plurality of disks 19, 20 and 21, of frusto-conical formation. The disk 21 is of considerably greater area than the disks 19 and 20 and is made of a material which is more flexible than the last named disks which are preferably made of metal. This will impart to the diaphragm greater rigidity adjacent its apex than where it is engaged by the outer portions of the disk 21. The latter disk is engaged with the inner surface of the diaphragm and the disks 19 and 20 are then engaged, respectively, with the outer surface of the diaphragm and the inner surface of the disk 21 with the result that said diaphragm and the latter disk will be interposed between the disks 19 and 20. By rea-

- son of this construction when vibrations are impressed upon the diaphragm at its apex the reinforcement of the diaphragm by the disks 19, 20 and 21 will minimize any tendency of a wave motion being imparted to the diaphragm as distinguished from a bodily movement of the diaphragm which actually occurs with the present construction. This bodily movement or vibration of the diaphragm is partly due to the fact that the periphery thereof is flexibly supported by the element 12 and not rigidly fixed as is customary with sound reproducers of known construction.
- In order that vibrations might be imparted to the apex of the diaphragm 13 a vibratory unit in the form of an electro-magnetic device, generally indicated by the numeral 22, is centrally disposed in the opening in the supporting ring 10 and carried by a cross piece 23, the ends of which are detachably secured to said ring in order that the unit may be removed whenever desired. The unit 22, which is an electrically modulated vibratory mechanism and is only conventionally illustrated in the present case, it being understood that any other suitable mechanism may be employed to impart vibrations to the diaphragm. This unit further consists of a rod 24 one end of which is connected to the armature of the electro-magnet contained in the unit 22 and the other end of which is extended through a terminal member 25 adjustable longitudinally of said rod and secured thereto by a suitable screw 26. The member 25 is provided with a reduced screw threaded shank 27 which projects into the opening 18 in the apex of the diaphragm and has mounted thereon a nut 28 which engages the disk 20 so that the various disks 19, 20 and 21 will be clamped between the head of the member 25 and said nut 28.
- A slightly different form of construction is shown in Figure 5 wherein the flexible support 29 instead of being formed like the support 12 of Figure 1 is cut to provide a spider-like construction consisting of a plurality of radiating arms 30, the outer ends of which are secured to the diaphragm 13 in the same way that the outer periphery of the support 12 is secured thereto. By this construction the amount of exposure of the inner surface of the diaphragm to unconfined air is increased and the nature of the resonance chamber formed between the flexible support and the diaphragm and the result obtained therefrom would be changed.
- Figure 8 illustrates the application of the inventive idea to a sound reproducer which may be employed in connection with talking machine records having vertically undulating grooves. In this construction the sound reproducer, which is of the same construction as shown in Figure 1 with the exception that the unit 22 is dispensed with, is supported in a horizontal position by an arm 31 pivoted at one end to a standard 32 and secured at its other end to the rigid ring 10. In this instance the apex of the diaphragm may receive and have secured therein a jewel ball or sapphire stylus 33 which is engageable in the grooves of a record 34.
- When used with records having laterally undulating grooves the reproducer is supported in a vertical position by an arm 35 pivotally connected to a standard 36. The arm 35 supports a stylus bar 37 to which is connected the usual stylus 38 and intermediate the ends of said stylus bar the same carries a rod 39 which extends into the reproducer and has its end connected to the apex of the diaphragm 13, preferably in the same manner that the rod 24 is mounted. Thus the vibrations imparted to the stylus bar 37 will be transmitted to the apex of the diaphragm 13.
- What is claimed is:
1. In an acoustical device, a diaphragm, a flexible support therefor secured to the diaphragm at a distance from its periphery, a rigid support for said flexible support, and a flexible binding element secured to said diaphragm and flexible support and extending about the periphery of said diaphragm.
  2. In an acoustical device, a conical diaphragm, a flexible support for said diaphragm secured thereto at a point inwardly of the periphery thereof, a rigid support for said flexible support, and a binding element extending about the periphery of said diaphragm and securing the same and said support together.
  3. In an acoustical device, a conical diaphragm, means for imparting a graduated rigidity thereto at its apex, a flexible frusto-conical support having its outer edge secured to said diaphragm at a distance from its periphery, and a flexible binding extending about the periphery of said diaphragm and overlapping the outer edge of said flexible support.
  4. In an acoustical device, a conical diaphragm, means for imparting a graduated rigidity thereto at its apex, a flexible support secured to said diaphragm, and a binding element extending about the periphery of said diaphragm and securing the same and said flexible support together.
  5. In an acoustical device, a conical diaphragm, a non-rigid support for the periphery thereof, reinforcing disks arranged on opposite sides of the diaphragm at its apex, and another reinforcing disk of greater flexibility than the first named disks secured to said diaphragm by the latter disks and extending outwardly beyond the peripheries thereof.

6. In an acoustical device, a conical diaphragm, a non-rigid support for the periphery thereof, reinforcing disks arranged on opposite sides of the diaphragm at its apex, and another reinforcing disk of greater flexibility than the first named disks secured to said diaphragm and extending outwardly beyond the peripheries of said reinforcing disks, and a binding element extending about 20 to the periphery of said diaphragm and overlapping a portion of said non-rigid support.
7. In an acoustical device, a diaphragm, a flexible support secured thereto adjacent its periphery and combining therewith to 25 form a resonance chamber, a centrally located ring forming a rigid support for said flexible support and also forming an entrance to said chamber, and means carried thereby and connected to said diaphragm for vibrating the same.
8. In an acoustical device, a diaphragm, a flexible support secured thereto adjacent its periphery and having a central opening, the diameter of which is less than the width 25 of the support from its periphery to the edge of said opening, said support combining with the diaphragm to form a resonance chamber therebetween, a ring secured to the flexible support adjacent to and surrounding 30 the opening therein and forming an entrance to said resonance chamber, and means carried by said ring in the entrance formed thereby and connected to said diaphragm for vibrating the same.

In testimony whereof I have affixed my signature.

VITALIS HIMMER.

DISCLAIMER.

1,593,406.—*Vitalis Himmer*, Mountain Lakes, N. J. LOUD SPEAKER. Patent dated July 20, 1926. Disclaimer filed July 10, 1929, by the patentee.

Hereby enters this disclaimer to claim 8 of said Letters Patent.

8. In an acoustical device, a diaphragm, a flexible support secured thereto adjacent its periphery and having a central opening, the diameter of which is less than the width of the support from its periphery to the edge of said opening, said support combining with the diaphragm to form a resonance chamber therebetween, a ring secured to the flexible support adjacent to and surrounding the opening therein and forming an entrance to said resonance chamber, and means carried by said ring in the entrance formed thereby and connected to said diaphragm for vibrating the same.
